HERMAN ILENBURG, OF PHILADELPHIA, PENNSYLVANIA, ASSIGNOR TO MACKELLAR, SMITHS & JORDAN.

Design No. 3,456, dated April 27, 1869.

DESIGN FOR PRINTERS' TYPE.

The Schedule referred to in these Letters Patent and making part of the same.

To all whom it may concern:

Be it known that I, HERMAN ILENBURG, (assignor to Mac Kellar, Smiths & Jordan,) of the city and county of Philadelphia, Pennsylvania, have originated and designed a new Design for Printing-Type, of which the following is a full, clear, and exact description, reference being had to the accompanying specimens, making part of this specification, in which the entire alphabet of capital letters is shown, made in accordance with my design, which design is preserved in the small letters, signs, figures, or symbols, when desired.

What is claimed as new, is—

The within-described design for a printing-type, as set forth.

H. ILENBURG.

Witnesses:

Wm. B. MAC KELLAR,
